POSITIVE DISPLACEMENT PUMP

Lyndus E. Harper, Kansas City, Mo.

Application November 1, 1939, Serial No. 302,360

5 Claims. (Cl. 103—38)

My invention relates to positive displacement pumps, and more particularly to a liquid feeding device of a pump-like character that will accurately meter the amount of liquid fed by each reciprocation of the pumping device.

It is a particular purpose of my invention to provide a positive displacement pump for accurately measuring small quantities of liquid. In order to accomplish this purpose it is necessary that an exact quantity of liquid be discharged by the pump for each cycle of operation thereof, that is, for each intake and discharge stroke. Preferably, this is accomplished by providing inlet and outlet valves for the pump, that are positively closed so that the outlet valve will be positively closed before the intake, or suction stroke, of the pump begins, and so that the inlet valve will be positively closed before the discharge stroke commences, it being, of course, also preferred, inasmuch as the material that is pumped is a substantially non-compressible liquid, that the outlet valve be opened at least as soon as the discharge stroke begins, and that the inlet valve be opened at least as soon as the suction stroke begins.

It is a further purpose of my invention to provide a pumping device of the above mentioned character, which comprises a chamber that is provided with an inlet and outlet connection, having positively operated valves controlling certain inlet and outlet connections, which are positively operated in a predetermined timed relation to the strokes of a reciprocable member, which varies the liquid capacity of the chamber, so as to produce a pumping action of the liquid that may be received within the said chamber from the inlet connection and discharged through the outlet connection. Preferably, the reciprocable means is operated in such a manner that there is an interval of short duration at the point of reversal of motion thereof between the alternating strokes thereof, during which said reciprocable member is stationary for a sufficient period of time, so that the inlet valve can close and the outlet valve open, and vice versa, without there being any possibility of there being movement of the reciprocable member in the wrong direction while either the inlet or the outlet valve is open, which would, of course, interfere with the accurate measurement of the liquid by means of the pumping device.

Preferably, my improved pumping device embraces means for varying the amount of liquid pumped per stroke of the pump, so that the measured amount of liquid furnished at a cer-

tain rate of rotation of the pump may be adjusted as desired, this being, preferably, accomplished by varying the length of the stroke of the reciprocable member. Preferably, adjusting means is provided for varying the length of the stroke of the reciprocable member, which is provided with indicating means thereon showing either the amount of liquid being pumped per stroke, or some other unit of measurement, or any arbitrary scale that may be decided upon, to indicate the desired adjustment. It is also desirable to operate the reciprocable member in a manner that the discharge stroke is relatively long and the suction stroke relatively short, so as to reduce the intermittent character of the supply of liquid from the discharge end of the pump, which necessarily exists due to the pumping cycle, in a single chambered pump. Furthermore it is desirable, in order to not have too great an inactive interval for the pumping device during which no reciprocation takes place, that the valves open and close abruptly, and suitable cam means for this purpose are, preferably, provided.

Preferably, my improved pumping device is driven by a rotatable member, which is provided with suitable means for reciprocating the reciprocable member, and has directly rotatably mounted thereon to rotate therewith, the cam means for actuating the valves. It will be obvious that not only can the capacity of the pump during any interval of time be varied by varying the stroke of the reciprocable member, but that this can also be varied by varying the speed of the rotatable means for reciprocating said member.

One of the purposes of my invention is to provide pumping means that comprises a diaphragm for varying the liquid capacity of the pump chamber, and one of the preferred means for flexing the diaphragm to vary said liquid capacity comprises a bore, or cylinder, in which a reciprocable plunger, or piston, operates, the surfaces of the piston, and cylinder being of such hard material that these can be made to fit so closely that liquid interposed between said piston, or plunger, and the diaphragm, will not leak past the engaging walls of said piston and cylinder, the liquid being, of course, of such viscosity as to prevent such leakage of liquid between said engaging walls, with the close fit provided between the same.

Other objects and advantages of my invention will appear as the description of the drawings proceeds. I desire to have it understood, how-

ever, that I do not intend to limit myself to the particular details shown or described, except as defined in the claims.

In the drawings:

Fig. 1 is a view partly in elevation and partly in vertical section of one form of my improved metering pumping device.

Fig. 2 is a section taken on the line 2-2 of Fig. 1, on an enlarged scale.

Fig. 3 is a section taken on the line 3-3 of Fig. 1, on an enlarged scale.

Fig. 4 is a section taken on the line 4-4 of Fig. 1, on an enlarged scale.

Fig. 5 is a fragmentary section taken on the line 5-5 of Fig. 1, on an enlarged scale.

Fig. 6 is a view similar to Fig. 1, of another form of my invention.

Fig. 7 is a section taken on the line 7-7 of Fig. 6, on an enlarged scale.

Fig. 8 is a section taken on the line 8-8 of Fig. 6, on an enlarged scale.

Fig. 9 is a view partly in elevation and partly in section of the adjustable eccentric used in the form of the invention shown in Fig. 6.

Fig. 10 is a section taken on the line 10-10 of Fig. 9, and

Fig. 11 is a view partly in elevation and partly in section of another form of my invention.

Referring in detail to the drawings, in Fig. 1 is shown a pumping device having a frame 20, upon a portion of which is mounted any suitable means for driving a shaft, such as the motor 21, which is shown as driving the shaft 22 through a worm drive reduction gearing, indicated at 23, said shaft being mounted in suitable bearings 24 on the frame 20, and having provided thereon a main driving cam 25 and the valve cams 26 and 27, said cams 25, 26 and 27 being fixed to said shaft to rotate therewith.

Mounted on said frame in any suitable manner in fixed relation thereto, is a pump chamber 28 made up of the sections 29 and 30, said sections 29 and 30 being secured together in liquid tight relation by suitable securing elements 31 clamping the gasket 32 between suitable clamping faces on said members 29 and 30. The member 30 is shown as being provided with an inlet passage 33 and an outlet passage 34. While the particular shape of the chamber 28 may be varied, and the particular arrangement of inlet and outlet passages may also be varied, it is important that the inlet and outlet passages be so located that no air pockets can develop in the chamber 28, as no compressible gases must be contained therein, in order that the device will operate to measure the liquid passing therethrough properly.

The member 29 is, preferably, provided with a tubular projection 35 having a bore 36, which serves as a cylinder for the reciprocation of the cylindrical plunger, or piston, 37 therein. A tight joint is provided between the member 35 and the member 37 reciprocating therein, by providing a suitable packing gland arrangement made up of the compressible packing 38, and the packing nut 39 engaging the external threads 40 on the member 35. The member 37 is reciprocated by means of the cam 25, said member 37 having an extension 41, which operates slidably through a suitable guide 42, and which is provided with a bracket 43 on the end thereof having bifurcations 44 providing a suitable mounting for a pivot 45 for a roller 46, which engages the cam 25 to reciprocate said member 37, it being, of course, obvious that the liquid capacity of the chamber 28, which comprises a portion of the bore 36

for certain positions of the plunger, or piston, 37 will be varied in accordance with the portion of the plunger, or piston, extending into said chamber 28 and its connected cylinder 36.

Means is provided for varying the amount of movement of the member 37 to vary the capacity of the chamber 28, the means shown varying the length of the return stroke so that the cam is only effective through a portion thereof when the stroke is reduced from its maximum. Any suitable means for varying the length of the stroke of the reciprocable member that operates in the chamber may be provided, the means shown comprising an adjustable stop member 47, which cooperates with a stop member 48 fixed to the extension of the member 37, a compression spring 49 being shown as being mounted between the member 48 and the nut 39 for returning the plunger 37 from its furthest projected position to make the roller 46 follow the cam until the stop 48 engages the stop 47. The stop 47 is made of such shape that the peripheral edge 50 thereof progressively extends from the pivotal axis of the member 47 a certain unit of measure for each predetermined unit of arcuate movement of the member 47 about its pivot, in this form of the invention shown, the member 47 being pivotally mounted on a headed pin 51, which screw-threadedly engages in a suitable threaded boss 52 in the frame 20, and which is provided with any suitable means, such as the cross bar 53 on the head 54 for tightening the same up when the member 47 has been moved to a desired adjusted position. A scale 55 is, preferably, provided on the member 47 and any suitable cooperating indicator, such as the knife edge projection 56, may be provided on the stop member 48 to indicate the adjustment of the member 47 to a desired length of stroke or volume of liquid pumped per stroke, the scale shown being merely arbitrary and for purposes of illustration, it being obvious that the same can be calibrated in any manner convenient to the operator of the device.

Referring to Fig. 3, it will be noted that the cam 25 is shown as being keyed to the shaft 22 and as having a cam surface made up of a low portion 57, which is concentric with the axis of rotation of the cam and a high portion 58, that is concentric with the axis of rotation of the cam. Between said portions 57 and 58 is an outwardly curved portion 59, which is steep adjacent the portion 57 and becomes less steep as it approaches the portion 58. Beyond the portion 58 is a gradually inwardly curved cam surface 60, which is much longer than the outwardly curved portion 59, and which extends to the portion 51. With the roller 46 in the position shown in Fig. 3 and the cam rotating in the direction indicated by the arrow, the roller will first travel along the cam portion 60 to move the piston, or plunger, 37 to the right in Fig. 1, causing a gradual decrease in the liquid capacity of the chamber 28 and causing discharge of the liquid through the outlet passage 34, if the valve controlling the same is open. This movement will continue until the concentric cam face 58 is reached, whereupon there will be no movement of the reciprocable member 37 until after said portion 58 has been passed and the portion 59 of the cam surface has been reached, whereupon the spring 49, which has been previously compressed, will move the roller 46 toward the left, as shown in Fig. 1, to keep said roller in engagement with the cam surface 59 and, with a maximum stroke of the

reciprocable member, this will continue until the cam surface 57, concentric with the axis of the cam 25, is reached, whereupon the reciprocation of the member 37 will be again halted until the cam face 60 engages the roller 46, whereupon a repetition of the cycle of movements of the reciprocable member takes place. If the member 47 is adjusted to shorten the stroke of the plunger 37 from the maximum, then the roller 46 will leave the cam surface 59 due to engagement of the stops, before the cam surface 57 is reached, and will not engage the cam surface 60 until a point thereon is reached beyond the junction of the cam surfaces 57 and 60, dependent upon the position of the adjustable stop member 47.

The inlet connection 33 extends from an inlet valve 61, which leads from a supply pipe 62. Said inlet valve is illustrated as being provided with a diaphragm 63, which, when in engagement with the seat 64, closes the valve so that no liquid can pass through the same in either direction, the inlet valve being shown as being closed in Fig. 1. It is, of course, understood that the valve seat 64 extends transversely of the passage through the valve 61 and that the diaphragm will engage the entire length of said seat to completely cut off the chamber thus formed at 65 in the valve 61 from the chamber formed at 66 on the other side of the seat 64. The diaphragm 63, preferably, comprises some compressible material, which, when in engagement with the seat 64, will form a tight seal between said diaphragm and said seat, even though small solid particles might adhere to the seat, the flexible material providing means for such small particles to bury themselves therein temporarily, so that these will not interfere with the sealing of the closure of the valve. The diaphragm is connected with a reciprocable member, such as the valve rod 67, in any well known manner, said valve rod having a collar 68 secured thereto and a compression spring 69 mounted between said collar and the valve body portion. Said rod-like member 67 also extends through a guide member 70 provided on the frame 20 and is provided with a bracket 71 secured to the end thereof, which is provided with bifurcations 72 mounting a pivot member 73 for the roller 74 that engages the cam 26.

Said cam 26 is provided with a high portion 75 and a low portion 76, which are concentric with the axis of rotation of the cam 26, said cam being, of course, keyed to the shaft 22. Inclined connecting portions 77 and 78 connect the low portion 76 and the high portion 75 of said cam. The compression spring 69 will hold the roller 74 constantly in engagement with the cam surfaces and the rotation of the cam 26 is in the direction of the arrow shown in Fig. 4. The inlet valve being closed in the position of the parts shown in Figs. 1 and 4, the roller 74 will be in engagement with the cam surface 75 until the inclined portion 77 is reached, whereupon the roller will travel through a very short arcuate movement of the cam 26 to the low portion 76 and will remain in engagement with said low portion 76 until the inclined portion 78 is engaged, whereupon the roller will travel along the inclined portion until the portion 75 is again reached, the travel along the inclined portion 78 being through a very small arcuate movement of the cam 26. Accordingly it will be seen that with the form of cam shown in Fig. 4, the inlet valve will be closed for a long interval, then open abruptly and remain open for a short in-

terval and will then again close quickly, and then again go through the same cycle of operations. The arrangement of the cams 25 and 26 on the shaft is such that the portion 75 of the cam 26 will be in engagement with the roller 74 during the entire time that the roller 46 is in engagement with the cam surface 60, and the roller 74 will still be in engagement with the cam surface 75 when the cam portion 58 engages the roller 46. However, as the roller 46 continues in engagement with the cam portion 58 the roller 74 engages the cam portion 77, opening the valve 61, said valve being completely opened and the roller 74 in engagement with the cam portion 76 at the time that the roller 46 begins engagement with the cam portion 59 and this engagement of the cam portion 76 by the roller 74 continues until the cam portion 57 has engaged the roller 46. However, during the major portion of the engagement of the cam portion 57 with the roller 46, the roller 74 is in engagement with the cam portion 78, so that the valve 61 is moved to closed position before the roller 46 is engaged by the cam portion 60. Thus there can be no accidental backward flow of liquid through the inlet passage 33 and the valve 61, and also no negative pressure created in the chamber 28 by means of the plunger 37, as during the entire suction stroke of said plunger 37, the inlet valve will be open, and during the entire discharge stroke of said plunger the inlet valve will be closed.

The outlet valve 79 is constructed in a similar manner to the valve 61 and is connected with the discharge pipe 80 in a similar manner, the seat 81 of said valve 79 cooperating with the diaphragm 82 in a similar manner to that previously described. The operating or valve rod 83 is connected with the diaphragm 82 in the same manner as is the rod 67 with the diaphragm 63 and the collar 84 and compression spring 85 operate in the same manner as previously described. A guide lug 86 may be provided on the frame 20 for the rod 83 and a bracket 71, such as previously described, is provided thereon for mounting the roller 87 that engages the cam 27. The cam 27 has a low portion 88, which has substantially the same arcuate extent as the high portion 75 of the cam 26, and a high portion 89, which has substantially the same arcuate extent as the low portion 76 of the cam 26. The inclined portions 90 and 91 connect the high and low portions of the cam, the roller 87 being held in engagement with all portions of the cam surface due to the provision of the compression spring 85. The cam 27 is related to the cam 25 in such a manner that while the roller 87 is in engagement with the cam portion 88 and the valve 79 is opened in consequence thereof, the roller 46 will be in engagement with the cam portion 60, and this engagement of the roller 87 with the cam portion 88 will continue until the cam portion 58 engages roller 46, whereupon the outlet valve 79 will be closed due to engagement of the roller 87 with the cam surface 90, causing movement of the rod-like member 87 to the right, engagement of the cam portion 89 with the roller 87 holding said valve in closed position until the cam portion 91 is reached, whereupon the roller engaging the cam portion 91 under the influence of the spring 85 will cause the valve 79 to be opened. Preferably, the cams 26 and 27 are so constructed that the valve 61 will not open until the valve 79 has already been closed and the valve 61 will close before the valve 79 is opened. Thus, while the cam portions 89 and

76 are of substantially the same arcuate extent, they are preferably not of exactly the same arcuate extent, the angle measuring the arc 76 being, preferably, slightly less than the angle measuring the arc 89, thus assuring such operation of the valves as above referred to.

It will be obvious that with this arrangement of valve cams and driving cam for the reciprocable pumping member, the intake action of the pump will be rapid and the discharge action of the pump will be relatively slow and gradual.

If this is of no importance, an eccentric can be used to drive the pump, or a cross head arrangement can be used. If either of these types of drives are used, the cams that operate the valves will, of course, have to keep the valves open through substantially half the stroke and the valves will have to open and close during the reversal of motion of the reciprocable member at opposite ends of the stroke. In an eccentric drive the rate of movement of the plunger, when the direction of movement reverses, is at first so very small that no harmful compression in the pump chamber will result therefrom. Also this can be taken care of in utilizing a diaphragm pump, the movement of the diaphragm being so small that any increase in the pressure of the liquid that might result momentarily could be taken care of by the diaphragm. Such an arrangement is shown in Figs. 6 to 10, inclusive, the frame therein being indicated by the numeral 20 and the pump chamber comprising the member 30, previously described, and a member 92, which is secured to the member 30 by securing elements 93 to clamp the peripheral edge of the diaphragm 95 between suitable seats on the member 30 and the member 92. Said member 92 is provided with guiding means for the reciprocable rod-like member 96, said guiding means comprising a tubular boss 97 provided on the spider-like body portion of the member 92. Said rod-like member 96 is secured to the diaphragm 95 in any suitable member so that a liquid tight chamber 98 is formed between the diaphragm and the member 30.

In order to protect the diaphragm 95 and prevent any undue flexing thereof adjacent the point of securement of the member 96 therewith, a pair of concavo-convex disk-like washers 99 are provided on opposite sides of the diaphragm 95. The end of the rod-like member 96 remote from the diaphragm is secured in a socket 100 of an eccentric sleeve 101. The eccentric sleeve and the adjustable eccentric provided in this form of the invention are shown more in detail in Figs. 9 and 10. The eccentric is mounted on a shaft 22, which is driven in the same manner as the shaft 22, previously described, and similarly mounted on the frame in the bearings 24. The eccentric 102 is keyed to the shaft 22, as will be evident from Figs. 9 and 10, while the eccentric sleeve has mounted within the same and between the eccentric 102 and said sleeve 101 a member 103 that has an eccentrically located opening therein of the same diameter as the eccentric 102, so that said eccentric 102 and said member 103 are relatively rotatable to adjust the relative positions thereof. The member 103 is freely rotatable within the eccentric sleeve 101, and is shown as having an outwardly directed flange 104 and a detachable side plate 105 thereon forming a channel, this being merely illustrative, as any suitable means may be provided for holding the sleeve 101 and eccentric 102 assembled for rotation of said eccentric within said sleeve. The

member 103 is also provided with an inwardly directed flange 106 cooperating with the side plate 105 to confine the member 102 therebetween.

5 The member 103 is adjustable to different positions relative to the member 102 by rotation of the member 103 relative to said member 102, by means of the handle 107, so as to obtain a different length of stroke for the member 106. A 10 clamp 108 held in clamping engagement with the eccentric member 103 by means of a screw-threaded headed member 108' engaging a threaded opening in the eccentric member 102 holds the members 102 and 103 in adjusted position. In Figs. 9 and 15 10 the parts are so adjusted that the rod 96 will not reciprocate, but by rotating the member 103 through 180 degrees the maximum throw of the eccentric and stroke of the member 96 is obtained, and, of course, any adjustment between 20 these two positions will give adjustments of the length of the stroke of the reciprocable member 96 between such maximum and minimum strokes. Any suitable scale can be provided for indicating the adjustment of the member 103 relative to 25 the sleeve 101 to indicate the desired adjustment of the eccentric to get the desired throw thereof and the desired stroke of the reciprocable member 96, such as shown in Fig. 9. The particular clamping means for holding the parts in adjusted position may be varied as desired.

30 The inlet connection 33 is connected with a conduit 109 and the outlet connection 34 is connected with a conduit 110. The conduit 109 is provided with an inlet valve 111 and the liquid supply pipe 62 leads into said inlet valve. Said 35 inlet valve may be of any desired construction, but is shown to be the same type of valve as the outlet valve, or discharge valve, 112, which is interposed between the conduit 110 and the discharge pipe 113. Each of said valves is provided with a tapered valve 114 provided on a rod-like member 115, and fixed in liquid tight relation to the member 115 is a disk-like member 116, an 40 accordion-like diaphragm member 117 being secured at one end to the member 116 and at the other end to the valve casing to provide for movement of the valve rod 115 and to provide at the same time a liquid tight connection between the valve casing and said valve rod. The guide members 10 and 86, previously described, are provided 45 for the valve rods 115, and said valve rods are provided with brackets 71 thereon, that rotatably carry the rollers 74 and 87, similar to those previously described in connection with Fig. 1. The 50 roller 74 engages a cam 117 and the roller 87 engages a cam 118, both cams being keyed to the shaft 22, as will be obvious from Figs. 7 and 8. The rollers 87 and 74 are held in engagement with the respective cams by means of the compression 55 springs 119 provided between the members 116 and the collars 68 and 84, provided on the two 60 rod-like members 115, in a similar manner as described in connection with Fig. 1.

65 In the position of the parts shown in Figs. 6, 7 and 8 the valve 111 is closed and the valve 112 is open. However, the position of the parts is such that the outlet valve member 114 in the outlet valve 112 will move into engagement with the seat 120 and the valve 111 will open upon 70 slightly further rotation of the cams than that shown in Figs. 7 and 8. Also, when this takes place the diaphragm 95 will be flexed to the left to increase the capacity of the chamber 98 due to the fact that the position of the eccentric 75 will be such that the rod-like member 96 will be

reciprocated toward the left, as viewed in Fig. 6. The cam 117 has a high portion 121 and a low portion 122, each concentric with the axis of rotation of the cam 117, and inclined portions 123 and 124 connecting said high and low portions, while the cam 118 has a high portion 125 and a low portion 126 concentric with the axis of rotation of the cam 118, and inclined portions 127 and 128 connecting said high and low portions of the cam. The rotation of the cams is in the direction of the arrows shown in Figs. 7 and 8. The roller 87, controlling the outlet valve, is in engagement with the low portion of the cam in the position shown, but the inclined portion 128 is just ready to engage said roller 87 so as to move the rod 115, controlling the valve 112, to the right to seat the valve 114 against the seat 120 and close said valve. This occurs substantially instantaneously, as the arcuate distance traveled by the cam 118 as said roller 87 rides along the inclined face 128 is very short, and this occurs at the time the eccentric causes the reversal of movement of the reciprocable member 96, at which time the movement of said reciprocable member in the direction of its length is very small compared with the amount of rotation of the eccentric that takes place.

It will be noted that the roller 74, at the same time that the roller 87 engages the low part 126 of the cam 118, is in engagement with the high part 121 of the cam 117 and that this engagement continues for an interval after the cam portion 128 engages the roller 87, and thus the inlet valve will remain closed until the outlet valve has been closed, whereupon the roller 74 will engage with the cam surface 124 and ride down along the same until the cam surface 122, or low portion of the cam 117, engages the roller 74, at which time the inlet valve 111 is wide open, while the outlet valve is held closed due to engagement of the high part of the cam 125 with the roller 87. In a similar manner the valve 112 will remain closed until after the inlet valve has again been closed, due to engagement of the inclined portion 123 of the cam 117 with the roller 74 and the high portion 121 thereof with said roller, this taking place when the reciprocable member 96 has reached the limit of its movement to the right, at which time the eccentric reaches a point at which such reversal takes place, but the movement of the member 96 in the direction of its length is very small in proportion to the amount of rotation of said eccentric. As a result there will be very little increase in pressure in the liquid in the chamber 98, due to the fact that both valves are closed while this slight movement of the member 96 is taking place under the action of the eccentric provided for reciprocating the same.

In case the metering action of the pump does not have to be as accurate as would be the case where the forms of the invention shown in Figs. 1 to 5, inclusive, and 6 to 10, inclusive, are utilized, the apparatus shown in Fig. 11 may be utilized to feed said liquid. The feed pipe 129 is provided with a ball check valve 130 connected by the conduit 131 with an inlet connection 132, which leads into the liquid chamber 133 provided in the member 30, the outlet connection 134 connected by a conduit 135 with a ball check valve 136 leading to the discharge pipe 137. A diaphragm 138 is clamped between suitable faces on the member 30 and the member 139, which is provided with a threaded hollow boss 140 thereon, with which a cylinder 141 is connected in liquid tight engage-

ment. Said cylinder 141 is, preferably, made of a very hard material, at least on the inner cylindrical surface thereof, providing the bore 142, said cylinder being, preferably, made of an alloy that can be nitrided, such as the alloy known as "Nitralloy," manufactured by the Ludlum Steel Company, which is a low carbon-manganese-silicon-chromium-molybdenum-steel alloy, containing aluminum. This alloy can be surface hardened so as to have such an extremely hard surface that it will not be scored and will not gall when used in the manner illustrated. A plunger, or piston, 143 of a cylindrical character is, preferably, made in a similar manner and is similarly nitrided to surface harden the same, said piston fitting the cylinder so closely that liquid contained in the chamber between the diaphragm 138 and the body of the member 139 will not escape between the walls of the piston, or plunger, and the inner surface of the cylinder, with which it slidably engages. This is possible because, due to the extreme hardness of the material, such a close fit can be provided without having excessive friction. The reciprocable member can be driven in any of the ways previously described, or can be driven by means of a rod 144 pivoted thereto and connected with a cross head 145, so as to be adjustable relative to the center of rotation of the member 146 carrying said cross head, so as to vary the stroke of the piston, or plunger, 143 by movement of the member 147 in the slot 148 provided in the member 145 rotating with the rotatable member 146.

A liquid, which is preferably thick, heavy and of high viscosity, such as a heavy-bodied grease, indicated at 149, is provided in the chamber between said diaphragm 138 and the wall of the member 139, said liquid being substantially non-compressible and being, preferably, of a character that it has such a viscosity that there can be no escape thereof between the wall 142 and the piston 143, said liquid, of course, entering the cylinder bore 142 that communicates with the chamber between the diaphragm 138 and the casting 139, and it being obvious that the diaphragm will be flexed, dependent upon the position of the piston 143, thus varying the capacity of the chamber 133 in accordance with the position of said piston 143, thus drawing in fluid through the check valve 130 and discharging it through the check valve 136 in a well known manner.

What I claim is:

1. A metering pump of the character described, comprising a pump chamber, a reciprocable member for varying the liquid capacity of said chamber, driving means for said reciprocable member, an inlet connection leading to said chamber, an inlet valve controlling supply of liquid to said chamber, an outlet connection leading from said chamber, an outlet valve controlling discharge of liquid from said chamber, said chamber being sealed whenever both said valves are closed, and means including cams positively driven by said driving means for opening and completely closing said valves in positively timed relation to each other and to the reciprocations of said reciprocable member, said driving means comprising means for moving said reciprocable member more rapidly in a chamber capacity increasing direction than in a chamber capacity decreasing direction.

2. A metering pump of the character described, comprising a pump chamber, a reciprocable member for varying the liquid capacity of said chamber, means for reciprocating said reciprocable member including driving means, means for ad-

justing said means for reciprocating said member to vary the length of the stroke of said reciprocable member, an inlet connection leading to said chamber, an inlet valve controlling supply of liquid to said chamber, an outlet connection leading from said chamber, an outlet valve controlling discharge of liquid from said chamber, said chamber being sealed whenever both said valves are closed, and means including cams positively driven in synchronism with said driving means for opening and completely closing said valves in positively timed relation to each other, said driven means positively holding both said valves closed over predetermined intervals, the means for reciprocating said member including means for holding said reciprocable member stationary whenever said chamber is sealed.

3. A metering pump of the character described, comprising a pump chamber, a reciprocable member for varying the liquid capacity of said chamber, means for reciprocating said reciprocable member including driving means, means for adjusting said means for reciprocating said member to vary the length of the stroke of said reciprocable member, an inlet connection leading to said chamber, an inlet valve controlling supply of liquid to said chamber, an outlet connection leading from said chamber, an outlet valve controlling discharge of liquid from said chamber, said chamber being sealed whenever both said valves are closed, and means including cams positively actuated by said driving means for opening and completely positively closing said valves in positively timed relation to each other and to the reciprocations of said reciprocable member, said means positively holding both said valves simultaneously closed over predetermined intervals, said means for reciprocating said member including means for holding said reciprocable member stationary whenever said chamber is sealed.

4. A metering pump of the character described, comprising a pump chamber, a reciprocable member for varying the liquid capacity of said chamber, means for reciprocating said reciprocable member including driving means, an inlet connection leading to said chamber, an inlet valve controlling supply of liquid to said chamber, an outlet connection leading from said chamber, an outlet valve controlling discharge of liquid from said chamber, said chamber being sealed whenever both said valves are closed, and means positively actuated by said driving means for opening and completely closing said valves in positively timed relation to each other, comprising

ing means including a cam for opening said outlet valve before the capacity decreasing stroke of said reciprocable member commences and holding said outlet valve open during the entire capacity decreasing stroke of said reciprocable member and means including a cam for opening said inlet valve before the capacity increasing stroke of said reciprocable member commences and holding said inlet valve open during the entire capacity increasing stroke of said reciprocable member, said means positively holding both said valves closed for intervals alternating with the periods during which said valves are alternately held open, said means for reciprocating said member comprising means for varying the length of the stroke of said reciprocable member between zero and full stroke without affecting the relation of said valve positions to the strokes thereof.

5. A metering pump of the character described, comprising a pump chamber, a reciprocable member for varying the liquid capacity of said chamber, means for reciprocating said reciprocable member including driving means, an inlet connection leading to said chamber, an inlet valve controlling supply of liquid to said chamber, an outlet connection leading from said chamber, an outlet valve controlling discharge of liquid from said chamber, said chamber being sealed whenever both said valves are closed, and means positively actuated by said driving means for opening and completely closing said valves in positively timed relation to each other, comprising means including a cam for holding said outlet valve open during the entire capacity decreasing stroke of said reciprocable member, and means including a cam for holding said inlet valve open during the entire capacity increasing stroke of said reciprocable member, said means positively holding both said valves closed for intervals alternating with the periods during which said valves are alternately held open, said means for reciprocating said member comprising means for holding said reciprocable member stationary during the intervals during which both said valves are closed and including means for varying the length of the stroke of said reciprocable member between zero and full stroke without affecting the relation of said valve positions to the strokes thereof, comprising resilient means for moving said reciprocable member in one direction and an adjustable stop for limiting such movement by said resilient means.

LYNDUS E. HARPER.
